FEEDING DEVICE

Fred M. Slater, Phillipsburg, N. J., assignor to
Ingersoll-Rand Company, Jersey City, N. J., a
corporation of New Jersey

Application April 30, 1936, Serial No. 77,153

8 Claims. (Cl. 121—9)

This invention relates to fluid actuated rock drills, and more particularly to a feeding device for advancing a rock drill of the stoper type in accordance with the penetration of the working element into the work.

One object of the invention is to protect the rock drill against injury by its percussive element when the feeding device is fully extended and the working implement has been actuated 10 out of the range of movement of the percussive element.

A further object is to automatically reverse the feeding element and to cut off the supply of pressure fluid to the rock drill when the feeding 15 device approaches or reaches a fully extended condition.

Other objects will be in part obvious and in part pointed out hereinafter.

In the drawing accompanying this specification and in which similar reference numerals refer to similar parts,

Figure 1 is a side elevation of a feeding device constructed in accordance with the practice of the invention and a rock drill to which it is applied,

Figure 2 is an elevation, in section, of the feeding device,

Figure 3 is a transverse view taken through Figure 2 on the line 3—3, and

Figures 4, 5 and 6 are elevations taken through Figure 3 on the lines 4—4, 5—5 and 6—6, respectively.

Referring more particularly to the drawing, 20 20 designates the feeding device in its entirety, 21 a rock drill connected to the feeding device, and 22 a working implement that extends into the rock drill 21 into the path of a hammer piston (not shown) whereby the working implement is driven into the rock 23 for drilling the hole 24.

The drilling mechanism may be supported by 40 any suitable means, as for example a column 25 having a clamping device 26 that engages the feeding device 20 and maintains the rock drill 21 in the correct operative position with respect to the work 23.

The feeding device 20, constructed in accordance with the practice of the invention, comprises a cylinder 27 which, in the present instance, constitutes the stationary member and is held thus by the clamping device 26. The cylinder contains a piston 28 having opposed differential pressure surfaces 29 and 30 and is connected to the rock drill 21 by a rod 31 carrying an external collar 32. The corresponding ends 50 of the rod 31 and the collar 32 seat against a head block assembly 33 comprising, in the structure shown, a series of plates 34, 35 and 36 of which the plate 34 lies adjacent the collar 32 and that designated 36 adjacent the rear end of the rock drill 21 for which it forms a closure.

The plates constituting the head block assembly are held in assembled relationship with respect to each other, and with the rock drill 21 and the collar 32, by bolts 37 extending through these elements and serving to clamp them securely together.

Within the plate 36 is a valve chamber 38 containing a throttle valve 39, of the rotary type, having a bore 40 into which pressure fluid is admitted by a supply conduit 41 connected to the 10 plate 36. The throttle valve 39 has a stem 42 projecting to the exterior of the plate 36, and on the free end of the stem 42 is a lever 43 whereby the throttle valve 39 may be manually actuated.

The throttle valve 39 controls the admission of pressure fluid to both the rock drill 21 and the feeding device 20. To supply the former the plate 36 is provided with a supply passage 44 which may lead to the distributing valve (not 20 shown) of the rock drill, the throttle valve 39 having a port 45 to register with the passage 44.

In the periphery of the throttle valve 39 is a partly annular groove 46 which is in constant communication with the bore 40 through a port 47 and registers with passages 48 and 49 that open into the valve chamber 38 in the same transverse plane. The passage 48 extends through the head block assembly and opens into a chamber 50 in the rod 31, and a passage 51 30 in the rod 31 affords communication between the chamber 50 and a pressure chamber 52 in the cylinder 27.

The passage 49 extends through the head block assembly and through the collar 32 and the wall of the rod 31 and opens into a tube 53 seated with one end into the plate 33 and with its other end in the portion of the rod forming an end surface for the chamber 50. The interior of the tube constitutes a continuation of the passage 49 and said passage is extended through the lower or free end of the rod 31 and opens into an enlarged pressure chamber 54 in the lower or outer end of the cylinder 27. The passages 48 and 49 are so arranged that the groove 46 may simultaneously communicate with both and the pressure chambers 52 and 54 may, therefore, be placed in communication with pressure fluid supply at the same time.

The throttle valve 39 is actuated manually, 50 by means of the lever 43, to the open position. Means are provided, however, to effect automatic shifting of the throttle valve for cutting off the supply of pressure fluid to the pressure surface 29 when the feeding device approaches or reaches a condition of maximum extension. To this end the plate 36 is provided with a piston chamber 55 to accommodate a swing piston 56 keyed to the valve stem 42. The piston chamber 55 is sealed by a cover 57 secured 55 60

to the plate 36, and a projection 58 on the cover 57 extends into the piston chamber 55 to form a head 59 for one end of the piston chamber.

An exhaust port 60 intermediate the ends of the piston chamber 55 provides an outlet for pressure fluid employed for actuating the piston 56, and in the inactive end of the piston chamber is a vent 61 to maintain that end of the piston chamber in constant communication with the atmosphere.

The surface of the swing piston 56 adjacent the head 59 constitutes a pressure surface 62 to which pressure fluid is conveyed by a passage 63 extending through the projection 58 and the head block assembly and opening into a tube 64 affixed to the plate 33 and the rod 31, in the manner of the tube 53. The interior of the tube 64 thus also forms a continuation of the associated passage 63, and said passage is continued through the rod 31 and communicates with the pressure chamber 52 through a port 65.

In order that the port 65 may be normally closed to prevent communication between the pressure chamber 52 and the passage 63 a valve 66, of the sleeve type, is disposed upon the rod 31 and is normally held in position to seal the port 65 by a spring 67 seating against the valve 66 and the piston 28. The spring 67 serves to hold the valve against a shoulder 68 on the rod 31 and on the end of the valve lying adjacent the shoulder 68 is an external flange 69 which, when the feeding device approaches maximum extension, is engaged by a head 70 of the cylinder 27 and caused thereby to uncover the port 65.

The flange 69, while of larger diameter than the rod 31 to permit of such engagement of the flange with the head 70, is of smaller diameter than the bore of the cylinder 27 to permit of the free passage of pressure fluid between the flange and the cylinder.

As a preferred form of construction, the throttle valve also performs the function of communicating the passages 48 and 49 with the atmosphere to permit the exhaust of pressure fluid from the pressure chambers 52 and 54. The throttle valve is, therefore, provided with a groove 71 located in the same transverse plane as the groove 46 to register with the passages 48 and 49, the groove 71 being of an extent to enable it to be placed in communication with both passages at the same time. The throttle valve is further provided with a longitudinally extending groove 72 to communicate the groove 71 with an exhaust port 73 in the plate 36.

In addition to the throttle valve as a means for controlling the exhaust of pressure fluid from the feeding device, the drilling mechanism is provided with the usual rotation handle 74 anchored to the plate 36 and having a grip portion 75 which the operator grasps to hold the rock drill 21 against unauthorized rotary movement. The grip portion 75 and the handle 74 have a passage 76 extending therethrough, and said passage 76 communicates with a passage 77 opening into the passage 49.

Communication between the passage 76 and the atmosphere is effected through a port 78 which is controlled by a valve 79, and a lever 80 pivotally connected to the grip portion 75 seats against the valve 79 and may be conveniently manipulated by the hand gripping the grip member 75 to open the passage 76 to the atmosphere. Thus, whenever the pressure within the pressure chamber 54 is found to be excessive, as

when the working implement is passing through a soft strata in the work and in which case there is danger of rifling the drill hole, the valve 79 may be unseated by means of the lever 80 to partially reduce the pressure within the pressure chamber 54.

The operation of the device is as follows: The throttle valve 39 is first actuated, by manual pressure against the lever 43, to the position illustrated in Figure 5 to bring the groove 46 into registry with the passage 48. Pressure fluid then flows through the chamber 50 and the passage 51 into the smaller pressure chamber 52 and acts against the pressure surface 30 to contract the feeding device and hold it thus preparatory to its correct arrangement with respect to the work. When the drilling mechanism is correctly placed the throttle valve is rotated further to also bring the groove 46 into registry with the passage 49. Pressure fluid then passes into the pressure chamber 54 to act against the larger pressure area 29 of the piston and simultaneously, or shortly thereafter, the port 45 is brought into registry with the passage 44 to supply pressure fluid to the rock drill for actuating it.

During the ensuing period of operation of the drilling mechanism the percussive element of the rock drill 21 drives the working implement 23 into the work, and as the working implement penetrates the work the pressure fluid acting against the pressure surface 29 constantly acts to advance the drilling mechanism in accordance with the degree of penetration of the working implement into the rock and thereby maintains the rock drill in correct operative relationship with the working implement.

This mode of operation will continue until the piston 28 reaches a position in the cylinder 27 in which the feeding device approaches full extension. The flange 69 will then engage the head 70 and as the piston, together with the rock drill 21, continues its feeding movement the port 65 is drawn out of the plane of the valve 66 and placed in communication with the pressure chamber 52. Pressure fluid then passes through the passage 63 into the cylinder 55 and acts against the actuating surface 62 of the piston 56 and actuates said piston for rotating the throttle valve.

The pressure fluid acting against the actuating surface 62 actuates the piston 56 in the manner described until said piston uncovers the exhaust port 60, whereupon the pressure fluid used for actuating the piston and the throttle valve is exhausted to the atmosphere through the port 60. The port 60, it should be understood, is so located that the active side of the cylinder 55 is communicated with the atmosphere when the throttle valve reaches the position in which the groove 46 is moved out of registry with the passage 49 although still in registry with the passage 48.

In the new position of the throttle valve the groove 71 registers with the passage 49 and the pressure fluid previously entrapped in the chamber 54 may then escape to the atmosphere. As soon as the effective pressure within the chamber 54 drops below that in the chamber 52 the pressure fluid in the latter chamber, acting against the surface 30 of the piston, immediately retracts the piston and the rock drill in readiness for a subsequent drilling operation.

After the feeding mechanism is again fully contracted the throttle valve may be further actuated in the direction of its closed position, by means

of the lever 43. The groove 71 will then register with the passage 48 and both pressure chambers 52 and 54 will be open to the atmosphere through the passages in the feeding device and the throttle valve.

From the foregoing description it will be readily apparent to those skilled in the art that the only manual attention required by the drilling mechanism is that of shifting the throttle valve 39 to the open position at the beginning of a drilling operation. The drilling mechanism will then continue to operate without any further attention from the operator until the cycle of operations has been completed or until it is again intended to start another round of operation. Although, whenever the nature of the rock being drilled is such that the full feeding pressure acting against the surface 29 is found to be excessive, the valve 79 may be opened to reduce the pressure acting against the pressure surface 29 to a value consistent with good drilling results under the circumstances. When the working implement again encounters stable rock the valve 79 may be permitted to close and the drilling mechanism will then again advance under full feeding pressure.

I claim:

1. A feeding device for rock drills, comprising a pair of relatively reciprocable members one of which is connected to the rock drill, pressure chambers in one of the members, opposed pressure surfaces on the other member, passages for conveying pressure fluid to and from the pressure chambers, a valve to control the passages and being manually actuated in one direction, an actuating surface on the valve, and means in one of the pressure chambers carried by one of the members and movable with respect thereto to valve pressure fluid to the actuating surface for actuating the valve in an opposite direction.

2. A feeding device for rock drills, comprising a pair of relatively reciprocable members of which one member is connected to the rock drill, pressure chambers in one of the members, opposed pressure surfaces on the other member, passages for conveying pressure fluid to the pressure surfaces to effect relative reciprocatory movement of the members, a valve to control the passages and being manually actuated in one direction, an actuating surface for the valve, and means carried by one of the members and actuated by the other member to valve pressure fluid from one of the pressure chambers to the actuating surface for shifting the valve in an opposite direction.

3. A feeding device for rock drills, comprising a pair of relatively reciprocable members of which one member is connected to the rock drill, pressure chambers in one of the members, opposed pressure surfaces on the other member, a rotary valve to control the flow of pressure fluid to the pressure surfaces to effect relative movement between the members and being manually rotated in one direction, a piston associated with the valve, and means carried by one member actuated by the other member for valving pressure fluid from one of the pressure chambers to the piston for rotating the valve in an opposite direction.

4. A feeding device for rock drills, comprising a pair of relatively reciprocable members of which one member is connected to the rock drill, pressure chambers in one member, opposed pressure surfaces on the other member, passages for conveying pressure fluid to and from the pressure

chambers, a valve to control the passages and having an actuating surface, a kicker passage in one of the members to convey pressure fluid to the actuating surface, a valve to control the kicker passage, and means on one of the members to move the last mentioned valve for admitting pressure fluid from one of the pressure chambers into the kicker passage for actuating the first said valve.

5. A feeding device for rock drills, comprising a feeding cylinder, a piston in the cylinder having opposed pressure surfaces, a rod on the piston connected to the rock drill and having a plurality of passages for conveying pressure fluid into the cylinder on opposite sides of the piston to act against the pressure surfaces, a valve to control the passages and having an actuating surface, a kicker passage in the rod for conveying pressure fluid from the cylinder to the actuating surface for shifting the valve, a valve on the rod to control the kicker passage, and means in the cylinder to effect shifting of the last said valve for uncovering the kicker passage.

6. A feeding device for rock drills, comprising a feeding cylinder, a piston in the cylinder having opposed pressure surfaces, a rod on the piston connected to the rock drill and having a plurality of passages for conveying pressure fluid into the cylinder on opposite sides of the piston to act against the pressure surfaces, a rotary throttle valve to control the passages, a lever on the throttle valve for rotating said throttle valve in one direction, a swing piston affixed to the throttle valve, a kicker passage in the rod for conveying pressure fluid from the cylinder to the swing piston for rotating the throttle valve in the opposite direction, a spring-pressed valve slideable on the rod normally preventing communication between the cylinder and the kicker passage, and means in the end of the cylinder to effect shifting of the last mentioned valve for communicating the kicker passage with the cylinder.

7. An extensible feeding device for rock drills, comprising a pair of relatively reciprocable members of which one member is connected to the rock drill, pressure chambers in one member, opposed pressure surfaces on the other member, passages for conveying pressure fluid to the pressure chambers, a valve to control the passages and being shiftable manually in one direction to admit pressure fluid into the passages, and means in one of the pressure chambers carried by one of the members and actuated by the other member to effect shifting of the valve in an opposite direction.

8. An extensible feeding device for rock drills, comprising a pair of relatively reciprocable members of which one member is connected to the rock drill, a piston on one member having opposed pressure surfaces, differential pressure chambers in the other member, passages for conveying pressure fluid to and from the pressure chambers, a valve to control the passages and being shiftable manually in one direction to supply pressure fluid to the pressure chambers, and means in the feeding device carried by one member and actuated by the other member to effect shifting of the valve for cutting off the supply of pressure fluid to and exhausting pressure fluid from the larger pressure chamber.

FRED M. SLATER.
